UNITED STATES PATENT OFFICE

CLARENCE E. STEVENS, OF CLEVELAND, OHIO, ASSIGNOR TO WHITE SEWING MACHINE CORPORATION, OF CLEVELAND, OHIO, A CORPORATION OF DELAWARE

BRACKET

Application filed March 30, 1928. Serial No. 265,950.

This invention relates to a metal bracket and the method of forming the same. It has particular utility in the manufacture of bracket posts used for connecting the backs 5 of certain types of chairs to the seats thereof as, for example, chairs commonly used in school rooms, although it should be understood that it is not limited alone to this use.

An object of the invention is to provide 10 a bracket for use as a seat post in connecting the backs of chairs to the seats thereof which is so formed as to provide a properly positioned back rest for the occupant of the seat.

Another object is to provide a metal 15 bracket of rigid construction which is easily attached in position on the parts to which it is applied.

Another object is to provide a metal 20 bracket which may be economically manufactured.

Other objects and advantages will become apparent as the description proceeds.

An embodiment of the invention is illustrated in the accompanying drawing, 25 wherein—

Fig. 1 is a side elevation of the seat and back portion of a school room chair, the bracket being used to connect such portions;

Fig. 2 is a front elevation of the seat and 30 back of the chair, a portion of the seat being broken away and shown in section;

Fig. 3 is a detailed view of the bracket; and

Figs. 4, 5 and 6 are sectional views taken 35 on lines 4—4, 5—5 and 6—6, respectively, of Fig. 3 and looking in the direction of the arrows.

Heretofore in the manufacture of brackets of this character it has been customary to 40 stamp the same from sheet metal blanks, which practice has resulted in considerable waste of material as there is always a large part of the blank which can not be used. In constructing the brackets according to the present invention, it is contemplated to eliminate 45 this waste of material and to effect a more economical production of the brackets by forming the same from strip stock. In carrying this out the strips of stock are first 50 cut into proper lengths to form the brackets

and at the same time a number of holes 10 are punched in the bars to be used for the passage of suitable securing means, such as wood screws. In punching the holes an annular bead 11 is formed on the outer side 55 of the bracket, the inwardly extending leg of which tapers inwardly as shown at 12 to form a countersunk recess for the reception of the screw head. It should be noted that the tapering portion of the opening terminates 60 in the plane of the inner side of the bracket, whereby the seat and back elements may lie flush against the bracket.

After the bar has been cut to length and the holes punched, a forming operation is 65 utilized for providing a substantially perpendicular flange 13 on one edge thereof extending the entire length of the bracket. Also, during this operation, one end of the bracket is rearwardly offset, as shown at 14, 70 for a purpose later to be described, and a strengthening rib or bead 15 is formed in the bracket intermediate its ends.

The bracket is then bent so that it will 75 have two arms 16 and 17 disposed at approximate right angles to each other. When in this form the strengthening bead or rib 15 will extend partly along the arm 16 and partly along the arm 17, so as to include the angular connection between the arms. 80

In order to strengthen the bracket an angle member 18 is welded or otherwise secured to the flange 13 at the junction of the two arms and is so formed that the part thereof which engages the angle of the bracket will 85 be considerably wider than either of its opposite ends, while the upper edge of the angle member is bent upon itself, as shown at 19, in Fig. 5, to form a strengthening bead the lower end of which is flanged inwardly at 20, as shown in Fig. 6, for a purpose later to be described. The flange 20 is merely a continuation of the portion 19 and is formed by twisting such portion outwardly at an approximate right angle to the main 90 body of the angle member.

When the bracket is used to connect the back and the seat of a school chair, it is, of course, necessary to employ right and left hand brackets. The arm 17 of the bracket 100

is attached to the seat 21 of the chair which rests upon the bracket with its edge in engagement with the flange 13. The seat 21 will extend rearwardly toward the arm 16 of the bracket and will be of such thickness that it will lie beneath the flange 20 of the angle member, while the rear edge thereof is preferably curved so that it will extend outwardly beyond the brackets, as shown at 22 in Fig. 1. The arms 16 of the brackets are connected by back supporting slats 23, one of which is attached to the offset portion 14 of the upper end of the arm, while the other is attached beneath such portion of the arm at 15 a point slightly above the upper end of the rib or bead 15.

These slats have their ends in engagement with the flanges 13 and are curved as shown at 24 in Fig. 1 so as to comfortably accommodate the back of the occupant of the chair, while the base of the arm 16 is bent or offset at 25 to enable the lower slat 23 to properly fit within the bracket and to lie flush against the base thereof. As already mentioned, in securing the brackets to the seat and back suitable means, such as wood screws, are passed through the openings 10. Because of the offset portion 14 at the upper end of the arm 16 the seat back will have a conformation properly arranged to receive the back of the occupant of the chair when sitting in a natural and comfortable position. Ordinarily chairs of this character are provided with backs which extend substantially straight upwardly or at a slight angle, instead of having portions of the seat back itself angularly disposed with respect to each other.

Although a preferred embodiment of the invention has been illustrated and described, it should be understood that the same is not limited thereto except in so far as the scope of the following claims so limits it.

Having thus described my invention, what I claim is:

1. A bracket adapted to be used as a post for connecting the seat and back of a chair comprising a metal strip flanged along one edge and angularly bent intermediate its ends so as to form angularly disposed arms each having a base portion and a flange portion, a strengthening rib formed in said strip and adapted to include the angle between the arms, one of said arms having an end angularly offset with respect to the remaining portion thereof, said arm also having a part of its base portion offset with respect to the remaining part thereof, and a strengthening angle member secured to the flange at the junction of the two arms of the bracket.

2. A bracket adapted to be used as a post for connecting the seat and back of a chair comprising a metal strip flanged along one longitudinal edge thereof and angularly bent

intermediate its ends so as to form angularly disposed chair seat and chair back receiving arms, respectively, each having a base portion and a flange portion, said chair back receiving arm having its upper end rearwardly offset whereby the configuration of the back of the chair will provide a properly positioned back rest for the occupant thereof, said last named arm having a part of its base portion offset with respect to the remaining part thereof. 70 75

3. A bracket adapted to be used as a post for connecting the seat and back of a chair comprising a metal strip flanged along one longitudinal edge thereof and angularly bent intermediate its ends so as to form angularly disposed chair seat and chair back receiving arms, respectively, a strengthening rib formed in said strip and adapted to include the angle between the arms, a strengthening angle member secured to the flange at the junction of the arms having a flange adapted to engage the upper side of the seat, and said chair back receiving arm having its upper end rearwardly offset whereby 80 85 90 95 the configuration of the back of the chair will provide a properly positioned back rest for the occupant thereof.

4. A bracket adapted to be used as a post for connecting the seat and back of a chair comprising a metal strip flanged along one longitudinal edge thereof and angularly bent intermediate its ends so as to form angularly disposed chair seat and chair back receiving arms respectively, each having a base portion and a flanged portion, a strengthening rib formed in the base portions of said strip and adapted to include the angle between the arms, a strengthening angle member secured to the flange portions of said arms at the junction thereof and having a flange adapted to engage the upper side of the seat, said chair back receiving arm having a part of its base portion offset 100 105 110 115 with respect to the remaining part thereof, and said last named arm also having its upper end rearwardly offset whereby the configuration of the back of the chair will provide a properly positioned back rest for the occupant thereof.

5. A bracket adapted to be used as a post for connecting the seat and back of a chair comprising a metal strip flanged along one longitudinal edge thereof and angularly bent intermediate its ends so as to form angularly disposed chair seat and chair back receiving arms respectively, and a strengthening angle member secured to the strip at the junction of the arms and having a flange adapted to engage the upper side of the seat. 120 125

In testimony whereof, I hereunto affix my signature.

CLARENCE E. STEVENS.
